UNITED STATES PATENT OFFICE

2,440,061

POWER-DRIVEN DRY SHAVER

Herbert E. Page, Alhambra, Calif.

Application April 30, 1945, Serial No. 590,998

3 Claims. (Cl. 30—43)

1

This invention relates to improvements in power driven dry shavers of the type employing a perforated cylindrical outer cutter head mounted for free rolling movement over the skin of the user and a rotatably driven inner cutter head mounted in the outer cutter head. Such a shaver is shown in my issued United States Letters Patent No. 2,355,672.

In such shavers the power driven inner cutter necessarily engages the inner surface of the outer cutter with enough friction to insure a close cutting of the whiskers projecting through the perforations in the outer cutter head and consequently there is a tendency for the inner cutter head to drag the outer cutter head along with it in its rotation. The rotation is at relatively high speed, say, of the order of 3,600 R. P. M. or over, and consequently when the outer head is first placed against the skin of the user, it is rotating with the inner cutter at such high speed that skin burn is apt to result.

It is an object of the present invention to overcome this difficulty and to provide a shaver of this general type wherein the inner cutter head is so constructed and operated that, in its rotation, it does not drag or cause rotation of the freely rotatable outer cutter head.

More specifically, it is an object of the present invention to provide a shaver of this type wherein the inner cutter head is composed of two separate, coaxial cutter elements disposed end to end and simultaneously driven in opposite directions.

Additional objects and advantages will appear from the following description of specific embodiments of the invention, for which purpose I shall refer to the accompanying drawings, in which:

Fig. 1 is a medial vertical section; and

Fig. 2 is a section on line 2—2 of Fig. 1.

Referring now to the drawings, Figs. 1 and 2, I show a hollow body 5 having an end recess 6 within which the cutter head assembly to be described is mounted.

A spindle 8 is carried by the body, on which the hub portion 9 of a cylindrical outer cutter head 10 is rotatably mounted, the cutter head 10 having perforations 11 adapted to pass whiskers.

Nested in axial alignment and end to end in the outer cutter head 10, there are two cylindrical inner cutter elements 15, 16, each having perforations 17 adapted to register with perforations 11. Cutter element 15 is fixed on a shaft 20 as by a key 21, while cutter element 16 is fixed by key 24 on a sleeve 23 journaled in the

body. A bevel gear 30 is secured on the outer end of sleeve 23 while an oppositely disposed bevel gear 32 is secured on shaft 20, both said gears being driven by a bevel gear 35 driven by a flexible shaft 36 from a conventional electric motor 37 mounted in the hollow body. The outer end of the shaft 20 is journaled in the body.

From the foregoing description it will be apparent that inasmuch as the gears 30, 32 are driven in opposite directions, the inner cutter elements 15, 16 are likewise driven in opposite directions so that although the peripheral portions of both inner cutter elements engage the inner surface of the outer cutter head with some friction, the tendency of each of the inner cutter elements to drag the outer cutter head is neutralized by the opposite rotational movement of the other inner cutter element, so that the outer cutter head remains stationary until pressed against and freely rolled over the skin surface during the shaving operation. As the outer cutter head is so rolled over the skin, whiskers on the face enter through the perforations 11 and into the perforations in the inner cutter elements 15 and 16 and are severed by the latter, which are driven to rotate relative to the outer cutter head.

While, in the foregoing, I have resorted to considerable detail of structure and association of parts in describing a particular example of my invention, I wish it to be understood that I have done so merely to make my invention understood and that I do not limit my invention to such details. On the contrary, my invention is only to be limited as appears in the appended claims.

I claim:

1. A dry shaver comprising: a body, a pair of coaxial inner cutter elements disposed end to end and rotatably mounted in the body, a perforated cylindrical outer cutter head mounted for rotating movement about the inner cutter elements and power means operatively connected to the inner cutter elements to rotate the same in opposite directions relative to each other whereby to neutralize drag of the inner cutter elements on the outer cutter head, said inner cutter elements and said outer cutter head having cooperating cutting edge portions.

2. In a dry shaver having a body, a spindle mounted in the body, an outer cylindrical perforated cutter head rotatably mounted on said spindle, a shaft journaled in the body coaxial with and disposed oppositely to the spindle, a sleeve rotatably mounted on and coaxial with the shaft, a pair of inner cutter elements dis-

posed end to end and nested in said outer cutter head, one of said inner cutter elements being fixed to said shaft and the other of said inner cutter elements being fixed on the sleeve, and power means operatively connected to the inner cutter elements to rotate them in opposite directions relative to each other.

3. In a dry shaver having a body and power means, an outer cylindrical perforated cutter head mounted on the body for free rolling movement over the skin of the user, a pair of inner cutter elements disposed end to end and nested in the outer head, and means operatively connecting the inner cutter elements to the power means, comprising a shaft journaled in the body 15 and fixed to one of the inner cutter elements, a bevel gear fixed on said shaft, a sleeve rotatably mounted on the shaft and fixed to the

other inner cutter element, a bevel gear fixed on the sleeve and disposed opposite the other bevel gear, a third bevel gear meshing with both said bevel gears whereby rotation of the third bevel gear rotates the other gears in opposite directions relative to each other, and means drivingly connecting the power means to the third bevel gear.
